UNITED STATES PATENT OFFICE.

EDWARD FRIEDRICH, OF SAN ANTONIO, TEXAS.

DESIGN FOR A BUTCHER'S FREEZER DISPLAY COUNTER.

Application filed March 30, 1923. Serial No. 5,653. Term of patent 14 years.

To all whom it may concern:

Be it known that I, EDWARD FRIEDRICH, a citizen of the United States, and resident of San Antonio, in the county of Bexar and State of Texas, have invented a new, original, and ornamental Design for Butcher's Freezer Display Counter, of which the following is a specification, reference being had to the accompanying drawing, forming a part thereof.

In the drawing:

Figure 1 is a perspective view of the counter looking from the front.

Figure 2 is a perspective view of the same looking from the rear.

I claim:

The ornamental design for a butcher's freezer display counter, substantially as shown.

EDWARD FRIEDRICH.
